UNITED STATES PATENT OFFICE.

EDWARD P. LYNCH, OF DAVENPORT, IOWA.

CULTIVATOR.

SPECIFICATION forming part of Letters Patent No. 257,228, dated May 2, 1882.

Application filed February 24, 1882. (No model.)

To all whom it may concern:

Be it known that I, EDWARD P. LYNCH, of Davenport, in the county of Scott and State of Iowa, have invented certain Improvements in Cultivators, &c., of which the following is a specification.

My invention relates to that class of wheeled cultivators and other machines in which vertically and laterally swinging drag bars or beams are employed to carry the shovels or other cultivating-instruments, and particularly to those machines wherein springs are employed to elevate or assist in elevating the beams above an operative position.

Various plans have been heretofore devised for applying the lifting-spring in connection with the beams, the most generally approved plan at the present time being that of providing a horizontal pipe-box or pipe-coupling, to which the beam is pivoted, with an upright arm jointed to the lower end of a vertically-sliding rod, which latter is urged downward by means of a spiral spring. To this construction there are various objections, one of which is that the downward pressure of the lifting-spring tends to cause undue friction between the axle and the coupling-box.

My invention is designed more particularly to avoid this difficulty by arranging a spring-actuated lifting-arm in such manner as to be entirely independent of the pipe box or coupling.

The accompanying drawings represent my device in its preferred form, the device being, however, susceptible of minor changes in form and arrangement.

Figure 1 represents a perspective view of one side of an ordinary wheeled cultivator with my device applied thereto. Fig. 2 represents a vertical central section through the same. Fig. 3 represents a longitudinal vertical section through the same.

The machine represented in the drawings is of the ordinary class of wheeled walking-cultivators, which consist of an arched frame or axle sustained at its ends by ground-wheels, and having vertically and laterally swinging bars coupled or jointed at their forward ends to the ends of the axle inside of the wheels. This type of machine being familiar to all persons skilled in the art, and forming no part of

the present invention, it is considered unnecessary to describe the same more in detail.

Referring to the drawings, A represents the arched frame or axle, having its two ends extended horizontally to receive the supporting-wheel B, as usual.

C represents a coupling box or sleeve mounted upon the horizontal end of the axle in such manner as to revolve freely thereon, the box being provided on its upper and under side with vertical studs or lugs a.

D represents one of the plow-bars, having its forward end fashioned into or provided with a bifurcated coupling head or jaw, b, which embraces the coupling-box C, with its arms mounted upon the journals a. The journals a permit the beam to swing laterally, while the rotation of the box around the axle permits the beam to be moved vertically, in the ordinary manner. The coupling-box and the coupling-head b may be of any ordinary or suitable construction, the box or sleeve C being cast in a single piece of tubular form, or made of two equal parts, as preferred, both plans being well known in the art.

E represents the beam-lifting arm, having its lower end forked or divided into two branches, c, which are arranged to straddle the coupling C, and are seated loosely upon and around the main axle D. The arm E thus mounted is free to revolve upon the axle independent of the pipe-box C, so that no strain or pressure of any kind is communicated therefrom to the box.

To the upper end of the arm E, I connect, by a horizontal pivot, e, the lower end of a vertical sliding rod, F, the upper end of which passes through a bearing or arm, G, secured rigidly to the side of the main axle or other suitable part of the machine.

Around the sliding rod F, I mount a spiral spring, H, the upper end of which will bear beneath the plate G, and the lower end will bear upon the pin or collar on the rod F, whereby the spring will be caused to urge the rod constantly downward.

To the coupling-pin e, or to either of the other parts in the immediate vicinity of the pin, I joint the upper end of a rod or chain, I, extending thence downward and backward to an eyebolt or other attaching device, f, upon the beam or drag-bar D.

Under the above-described arrangement of parts it will be seen that when the beam is down in an operative position the axle, the pivot *e*, and the upper end of the rod *H* will stand in the same, or substantially the same, plane as represented in Fig. 1, so that little or no strain is exerted upon the beam. When, however, the beam is elevated, the arm *E* is tipped forward, throwing the pivotal point *e* 10 out of line with the axle and the bearing *G*, whereupon the rod *H*, pressed downward by the spring, urges the arm *E* forward upon the axle, at the same time causing the rod *I* to exert a lifting strain upon the beam, this strain tending to elevate the beam above its operative position and lifting the shovel from the ground.

It will be observed that the rod *I*, with its devices, is located directly or substantially 20 above the vertical axis *a*, so that the beam is permitted to swing laterally with perfect freedom while subjected to the lifting action of the rod.

In order that the beams may be suspended 25 in such position as to retain the shovels at the proper depth in the ground, I provide the vertical rod *H* with a forwardly-projecting arm or finger, *J*, and the arm *E* with a forwardly-projecting finger, *K*, and between these two fingers I mount a strong spiral spring, *L*. During the elevation of the plows the spring *L* has little or no effect; but as the beams approach an operative position the arms *J* and *K*, moving-toward each other, cause the compression 35 of the spring *L*, which is made sufficiently strong to check the approach of the arms when the beam has reached an operative position, the spring then holding the beams suspended in the position required. The elasticity of the 40 spring *L*, however, permits the shovels to be depressed, when required, slightly below their normal position, the spring returning them to such position when they are released.

Although it is preferred to employ the spring 45 *L*, it is not a necessary element of the combination, as the lifting mechanism first described may be employed either with or without this secondary spring.

While it is preferred to mount the arm *E* up- 50 on the axle, it may be mounted upon a separate bearing immediately above or below the axle; but as such an arrangement would mod-

ify and to an extent impair its action the arrangement represented in the drawings is preferred.

While it is preferred to make use of the spiral spring, as represented in the drawings, it is manifest that any other suitable spring which will urge the arm *E* forward and downward may be employed—such, for example, as the arched or bent spring represented in dotted lines in Fig. 2.

Having thus described my invention, what I claim is—

1. In a wheeled cultivator, the combination 65 of the axle, the vertically and laterally swinging beam journaled to the axle, the lifting-arm journaled upon the axle independently of the beam-coupling, the vertically-sliding rod jointed to the lifting-arm, the spring depressing 70 said rod, and the connection extending from the lifting-arm to the beam, substantially as shown and described.

2. The combination of the axle, the coupling-box mounted upon the axle, the beam 75 jointed to the coupling-box, the lifting-arm mounted upon the axle independently of the coupling-box, the vertical rod jointed at one end to the lifting-arm, the spring, and the connection from the beam to the lifting devices, 80 substantially as shown.

3. In combination with the laterally and vertically swinging beam, the lifting-arm arranged to swing about a horizontal axis, and a jointed connection between the lifting-arm 85 and the beam, and a spring, applied substantially as described, to urge the upper end of the lifting-arm downward.

4. In combination with the beam, the axle, and the coupling-box connected to said parts, 90 the lifting-arm arranged to straddle the coupling-box and connected by intermediate devices, substantially as shown, with the beams.

5. The combination of the axle, the coupling-box, the beam, the lifting arm independent of the coupling-box, the connection between the lifting device and the beam, the vertical rod with forward extension at its foot, and the two springs, applied substantially as 95 described and shown.

EDWARD P. LYNCH.
